(57) **CLAIM**

The ornamental design for a freezer, as shown and described.

DESCRIPTION

FIG. 1 is a front and right side perspective view of a freezer with the freezer cover embodying the inventive design being closed;

FIG. 2 is a front elevation view of the freezer of FIG. 1 with the freezer cover embodying the inventive design being closed;

FIG. 3 is a back elevation view of the freezer of FIG. 1 with the freezer cover embodying the inventive design being closed;

FIG. 4 is a left side elevation view of the freezer of FIG. 1 with the freezer cover embodying the inventive design being closed;

FIG. 5 is a right elevation view of the freezer of FIG. 1 with the freezer cover embodying the inventive design being closed;

FIG. 6 is a top plan view of the freezer of FIG. 1 with the freezer cover embodying the inventive design being closed;

FIG. 7 is a front/right side perspective view of a freezer comprising the freezer cover embodying the inventive design in which the freezer cover is opened;

FIG. 8 is a front and right side perspective view of a freezer with the freezer cover embodying the inventive design being opened;

FIG. 9 is a left elevation view of the freezer of FIG. 7 with the freezer cover embodying the inventive design being opened; and,

FIG. 10 is a right side elevation view of the freezer of FIG. 7 with the freezer cover embodying the inventive design being opened.
